US00D533643S

(12) **United States Design Patent** (10) Patent No.: **US D533,643 S**
Veltz (45) Date of Patent: **** Dec. 12, 2006**

(54) HANDLE HUB	D318,906 S	8/1991	Spangler
(75) Inventor: Jason D. Veltz , Laguna Hills, CA (US)	D320,434 S	10/1991	Rawald
(73) Assignee: Newfrey LLC , Newark, DE (US)	D321,039 S	10/1991	Robbins
(**) Term: 14 Years	D325,426 S	4/1992	Paul
(21) Appl. No.: 29/234,316	D325,427 S	4/1992	Paul
(22) Filed: Jul. 15, 2005	D325,772 S	4/1992	Carr
(51) LOC (8) Cl. 23-01	D325,773 S	4/1992	Paul
(52) U.S. Cl. D23/249; D23/254	D326,504 S	5/1992	Robbins
(58) Field of Classification Search D23/238-257; D8/250-257, 300-322, DIG. 3; 16/110.1; 4/675-678; 137/801	D327,531 S	6/1992	Ko
See application file for complete search history.	D327,532 S	6/1992	Ko

Primary Examiner—Louis S. Zarfas*Assistant Examiner*—Gregory Andoll(74) *Attorney, Agent, or Firm*—Richard J. Veltman; John D. DelPonti

(57) **CLAIM**

The ornamental design for a handle hub, as shown and described.

DESCRIPTION

FIG. 1 is a perspective view of the new design for a handle hub;

FIG. 2 is a front view of the new design for a handle hub, the back, right side, and left side views being mirror images; FIG. 3 is a top view of the new design for a handle hub; and, FIG. 4 is a bottom view of the new design for a handle hub. The broken lines in the Figures are for illustrative purposes only and form no part of the claimed design.

1 Claim, 2 Drawing Sheets
